UNITED STATES PATENT OFFICE.

FRED C. JOSEPH, OF NEW YORK, N. Y.

DESIGN FOR A JEWELRY SETTING.

Application filed October 19, 1927. Serial No. 23,790. Term of patent 7 years.

To all whom it may concern:

Be it known that I, FRED C. JOSEPH, a citizen of the United States and a resident of the city of New York, in the county of the Bronx and State of New York, have invented a new, original, and ornamental Design for a Jewelry Setting, of which the following is a specification, reference being had to the accompanying drawing, forming part thereof.

In the drawings:

Fig. 2 is a side elevation.

Fig. 3 is an end elevation.

I claim:

The ornamental design for a jewelry setting, as shown.

Signed at 268 E. 169th St., in the county of Bronx and State of New York this fifteenth day of October, A. D. 1927.

FRED C. JOSEPH.
